DESIGN FOR A SANDAL

Harry Kaplan, Philadelphia, Pa.

Application July 23, 1934, Serial No. 52,669

Term of patent 7 years

To all whom it may concern:

Be it known that I, Harry Kaplan, a citizen of the United States, residing at Philadelphia, in the county of Philadelphia and State of Pennsylvania, have invented a new, original, and ornamental Design for Sandals, of which the following is a specification, reference being had to the accompanying drawing, forming part thereof. Figure 1 is a side elevation and Figure 2 is a plan view of a sandal showing my new design.

I claim:

The ornamental design for a sandal substantially as shown.

HARRY KAPLAN.
